US0D1042596S

(12) **United States Design Patent** (10) Patent No.: **US D1,042,596 S**
(45) Date of Patent: ** Sep. 17, 2024

(54) **MONITORING CAMERA**(71) Applicant: **Masimo Corporation**, Irvine, CA (US)(72) Inventors: **Chad A. DeJong**, Los Angeles, CA (US); **Jinwoo Kim**, Los Angeles, CA (US)(73) Assignee: **Masimo Corporation**, Irvine, CA (US)(**) Term: **15 Years**(21) Appl. No.: **29/868,706**(22) Filed: **Dec. 12, 2022**(51) LOC (14) Cl. **16-01**

(52) U.S. Cl.

(57) **CLAIM**

The ornamental design for a monitoring camera, as shown and described.

DESCRIPTION

FIG. 1 is a top perspective view of a monitoring camera showing our new design;

FIG. 2 is another top perspective view thereof;

FIG. 3 is a bottom perspective view thereof;

FIG. 4 is a rear perspective view thereof;

FIG. 5 is a front view thereof;

FIG. 6 is a rear view thereof;

FIG. 7 is a top view thereof;

FIG. 8 is a bottom view thereof;

FIG. 9 is a side view thereof; and,

FIG. 10 is another side view thereof.

Broken lines, where shown, are used to illustrate portions of the monitoring camera that form no part of the claimed design.
